(No Model.)

G. F. DURANT & H. L. BAILEY.
C. A. BAILEY, Administratrix of H. L. BAILEY, deceased.
TELEPHONE EXCHANGE SYSTEM.

No. 394,914.

Patented Dec. 18, 1888.

UNITED STATES PATENT OFFICE.

GEORGE F. DURANT, OF ST. LOUIS, MISSOURI, AND HENRY L. BAILEY, OF BROOKLYN, NEW YORK; CORNELIA A. BAILEY ADMINISTRATRIX OF HENRY L. BAILEY, DECEASED.

TELEPHONE-EXCHANGE SYSTEM.

SPECIFICATION forming part of Letters Patent No. 394,914, dated December 18, 1888.

Application filed May 10, 1888. Serial No. 273,423. (No model.)

To all whom it may concern:

Be it known that we, GEORGE F. DURANT, a citizen of the United States, residing at St. Louis, in the State of Missouri, and HENRY L. BAILEY, a citizen of the United States, residing at Brooklyn, in Kings county, and State of New York, have invented certain new and useful Improvements in Preventing Induction in Telephone-Lines and in Telephone-Exchange Systems, of which the following is such a full, clear, and exact description as will enable any one skilled in the art to which it appertains to make and use the same, reference being had to the accompanying drawings, forming part of this specification.

The object of our invention is to diminish the ringing induction in telephone-lines, and also to indicate to the operator at the central office that the lines are busy, or that a line is connected with another line, or to indicate that the subscriber has failed to replace the telephone on his hook, all of which give the busy test. Telephone-lines as they leave the central station are for considerable distance bound together in a strand, or are arranged in the neighborhood of other telephone-lines, so that when a fluctuation of current takes place in one wire it induces currents in the neighboring wire or wires, and thus interferes with the operation and functions of these line-wires. The most serious induction is caused when ringing subscribers up, for by the contrivances now employed when the subscriber's bell rings the circuit of his line is made and broken by his bell-magnet, so that the current on his line rises from and falls to zero as said bell vibrates. This gives rise to a great fluctuation of current and causes serious induction in neighboring wires, which induction seriously interferes with their operation. So, too, some lines being short and some long, when the same battery is used to ring up these different lines a battery that would produce sufficient current in the long line to ring the subscriber's bell would produce a strong current in the short line, so that when the short line is made and broken by the rheotome-bell the fluctuation of current is between much wider limits, for the

strength of it varies in this case from zero to 50 the increased strength just spoken of.

Our invention consists, first, in making the resistance of the various lines substantially equal within certain limits, so as to remove this increased inductive effect just alluded to, 55 and in using in connection with said equalized lines a bell-magnet with a shunt, so that the magnet will not make and break the circuit, but merely cut in and cut out its own resistance.

Our invention consists, secondly, in providing the operators at the central station of a telephone-exchange system having equalized lines and bell-magnets, as described, with an arrangement of signaling-circuits and circuit-controllers, that said operators at the central station may know when any line is in use or not left in its normal condition.

We will describe our invention as applied to a system known as the "Law" telephone system, shown and described in Patents Nos. 220,874, 225,797, 278,613, 294,851, and 319,856. We would here remark, however, that our invention could be used with other forms of switch-board than the Law.

We will now describe our invention in detail by referring to the accompanying drawings, making a part of this specification.

Figure I is a diagrammatic view of a central office provided with the Law switch-board 80 having our invention applied thereto and the telephone-lines radiating therefrom provided with our other improvements. Fig. II is a section of our non-inductive resistance signaling-plug.

The same letters of reference indicate the same or corresponding parts throughout the drawings.

A, B, C, and D designate four sections of a Law switch-board. At the center of said sections is left a space for the flexible connections. Some of these flexible connections we have shown diagrammatically at the center of the different sections by black dots. The fixed terminals of the subscribers we have indicated diagrammatically by small circles to distinguish them from the flexible terminals. In the switch-board we have shown a series

of lines passing therethrough and represented a fixed terminal of each line in each section of the switch-board. One flexible terminal of each line occurs in its respective section of 5 the switch-board, the flexible terminal being represented as connected with the wires passing through the switch-board by dotted lines. This is the Law switch-board, and will be understood by reference to the foregoing parts.

1 2 3 3' 4 4' 5 5' are the series of telephone-lines passing through the board and extending to the subscribers S', S², S³, S⁴, S⁵, S⁶, S⁷, and S⁸, connected, respectively, to said lines.

15 Each subscriber is provided with a subscriber's outfit, as represented in the diagram, consisting of a bell, a bell-magnet, a telephone-receiver, and a transmitter. The receiver and transmitter are arranged so as to be placed in 20 the main circuit of each line when the telephone is taken off the hook. When the telephone is on its hook, the transmitter and receiver are short-circuited to ground by way of said hook and a second contact, *m*, against 25 which the hook is held by the weight of the telephone, the same as in the case of the contact *n*. Each receiver normally hangs upon a spring-actuated hook of any suitable construction. Two terminals, *t*, of the primary circuit of the 30 transmitter are preferably arranged above the telephone-hook, so that when the telephone is removed therefrom the hook will be placed in the contact with said terminals and complete the primary circuit of the transmitter. These 35 features make no part of our invention. In the old construction the bell-magnet, when a subscriber is signaled, makes and breaks the main circuit, cutting in and cutting out the magnet. This, as pointed out above, causes the 40 current on the line to vary from zero to its normal strength, so that it will induce currents in neighboring wires, causing serious interference with telephone service. To obviate this, we arrange a shunt, *s*, around the bell-magnet. 45 The shunt is completed in the first instance by the armature of the bell-magnet coming against a contact, *q*, arranged near said armature. The shunt is connected to ground by way of the telephone-hook, which normally 50 rests against a contact, *r*, against which the phone-hook is held by the weight of the receiver. When the telephone is removed from the hook, the spring will draw the hook backward and break the circuit of the shunt. 55 When, however, the hook is in its normal position against the contact *r* and a signal is sent over the line, the shunt will be alternately made and broken at the contact *q*, and thus the bell-magnet only will be cut in and cut out of 60 circuit, the main circuit always remaining intact. Let us say, for instance, that the main-circuit resistance is two hundred ohms and the bell-magnet thirty-five ohms. If this circuit is made and broken, the resistance will 65 vary the full quantity of two hundred and thirty-five ohms. This will cause serious induction in neighboring wires. By our ar-

angement the resistance of the magnet only is cut in and cut out of circuit, thus making in the instance supposed a variation of thirty-five ohms as against two hundred and thirty-five ohms by the old arrangement. This of itself would greatly diminish ringing-induction in telephone-lines and result in a great benefit to the service.

75 The lines represented in the diagram are supposed to be of different lengths, and are preferably grounded at each subscriber; but a complete metallic circuit could be used as well. In signaling subscribers in the Law and other systems a battery common to all operators is used, or independent batteries all of substantially equal strength. In signaling over short lines, therefore, a strong current will be thrown upon the line, and when signaling a long line with the same battery a comparatively weak current will be thrown upon the line. The battery or batteries of course have to be made of such capacity that they can signal the long line, and when so 80 made and used upon a short line it will cause in said latter line a stronger current than desired, and one which when subjected to fluctuations will set up strong induced currents in neighboring wires. So it is obvious that 85 by using our shunt bell-magnet the difficulties, although greatly diminished, would not be entirely removed. We therefore combine 90 with this arrangement of ours another feature which constitutes another part of our invention, which is peculiarly adapted to our shunt-magnet. This feature consists of a non-inductive resistance, *R*, which is placed in the various lines, so as to make the resistance of all of them practically equal within certain 95 limits, so that the variation of current caused by signaling a line of low resistance and a line of high resistance is obviated. This non-inductive resistance may consist of a coil of wire which is wound back upon itself, so as to prevent the self-induction of the coils thereof upon one another. The non-inductive resistance may be placed at the subscriber's end of the line or at the central office, or at any point intermediate thereof. The resistance of the 100 lines by this means may be made absolutely the same, or can be practically made to vary between certain limits only. This non-inductive resistance can be placed in the operators' signaling-plug, if desired. The plug, 105 which is shown in detail in Fig. II, could in this instance have the non-inductive resistance arranged within the shell *P*, the battery being connected to the terminal *x*, which is 110 in electrical communication with one end of the non-inductive coil, the other end of said coil being connected with the signaling-tip *y*. This signaling-tip *y* is made to reciprocate in the plug *P*, and is held in its normal position by a spiral spring, *z*, which is arranged within said plug. The tip *y* is extended in the plug and terminates a short distance from but just opposite to the battery-terminal *x*. When signaling a short line, the 115 120 125 130 135

operator would merely touch the terminal of said line with the tip *y*. The resistance *R* would therefore be inserted in the line and bring the resistance of the short line up to or 5 near a circuit standard. When a long line is to be signaled, the operator would insert the tip *y* into the terminal of said line and press down thereupon, which would bring the extension of the tip *y* into contact with the terminal *x* and cut out the non-inductive resistance. In the Law or other systems the lines are so numbered and arranged in the switch-board that the operators know by the location thereof, or by the numbers, that the line is a 10 long or short one, so they are enabled to short-circuit or leave the resistance *R* in circuit. The signaling-plug *P* could be arranged in various ways so as to graduate the resistance thereof. The device shown in the drawings 15 and described in detail illustrates but one way of carrying out this feature of our invention.

Passing around the switch-board at the central office to each of the subscribers thereof 20 is a signaling-circuit, *N*, which is grounded or connected with the return-circuit emanating from each subscriber. In this circuit is connected a battery, *O*. The operators' signaling-plugs *P* are preferably connected in 25 multiple arc with said battery, and to serve this purpose the battery *O* should be made of very low internal resistance, so that several lines could be signaled at the same time without causing appreciable variation in the current. Said battery may preferably be an 30 accumulator or storage-battery, which is well adapted for this purpose. Independent signaling-batteries of uniform strength could be used by each operator, if desired, but the multiple-arc arrangement is preferred. The signaling-plugs are connected with the circuit *N* by a split circuit having two branches, in 35 one of which branches is arranged a small telephone, which is positioned near the ear of the operator. In the diagram we have shown two such telephones to each section (designated *a* *a'* *b* *b'*, &c., respectively)—that is to say, there would be two operators, one upon each side of each section of 40 the switch-board. In the other branch of the split circuit is arranged a magnet, *l*, the armature of which is in the circuit of the other branch of the split circuit. The action of the magnet *l* when abnormally energized is to 45 draw down its armature and break the circuit of the head telephone, which we will herein-after denote the "telephone-buzzer." The Law system is provided with a buzzer corresponding in functions to the telephone-buzzer we have described, the purpose of 50 which is to indicate that a line is busy. This is fully set forth in Patent No. 319,856 above, the arrangement in said patent being such that the subscriber when he lifts the telephone 55 from his hook cuts the bell-magnet out of circuit, so that when an operator in another section touches the terminal of said subscriber

her buzzer, which responds to the vibration of the bell, fails to give forth any sound, which means that the line is busy, for when the telephone is on the hook and the line in its normal condition her buzzer would vibrate in response to the subscriber's bell vibrations, which indicates that the line desired is not busy. In our arrangement, the bell-magnet 60 being always in circuit, some means has to be devised to indicate "not busy" when two lines are connected. This is the purpose of the split circuit and magnet *l*. Our arrangement also indicates that a line is not in its normal 65 condition, the same as the Law system, and when any line is not in its normal condition our arrangement, as well as the Law, gives the signal of "busy." For the successful operation of the system a line that is not in its 70 normal condition, whether it be connected or unconnected with any other line, is considered busy.

The diagram shows the system under all 75 possible conditions.

Before describing in detail the operation of the system it may be well in passing to state that the Law system is provided with call-circuits that are independent of the talking-circuits. In the diagram in the accompanying 80 drawings the talking-circuits only are shown. A subscriber in the Law system calls over the call-circuit to the operator at the central office, and before the operator at the central office connects the flexible terminal of the talking-circuit of the calling subscriber with the talking-circuit of the called subscriber she touches 85 the fixed terminal of the called subscriber with her signaling-plug. This signals the called subscriber and notifies him that he is 90 wanted, and at the same time serves to tell the operator whether the called subscriber is busy. If she gets a not-busy test, she makes the connection; but if she gets a 95 busy test by so signaling the called subscriber she notifies the calling subscriber that the line wanted is busy. Each subscriber in 100 the Law system also is provided with an individual talking-wire. These matters are alluded to herein so as to make the present system 105 readily understood, the details of the same being fully described in the patents set out above:

First. The line 1 is represented in its normal condition and the operator at *b* is represented as signaling such line by touching its terminal in her section of the switch-board with her plug. This sends a current over the line 1, said current passing by both branches of the split circuit to the signaling-plug, and from thence over the line through the bell-magnet and to ground, returning to the battery. The bell of the subscriber *S'* will vibrate, the shunt-circuit thereof will be made and broken, and the variation of resistance, 120 caused by the cutting in and cutting out of the bell-magnet, will set up in the telephone-buzzer *b* a series of vibrations, which will indicate to said operator that the line 1 is not 125

busy—that is, is in its normal condition. It may be here remarked that the buzzer-telephones are made insensitive—that is, sluggish in action—so as not to respond too readily to changes in the line. The current which passes through its branch of the circuit is not sufficient to draw down its armature, so that both branches of the split circuit remain intact.

10 Second. Let us suppose now that the line 2, for instance, be signaled, which has its telephone off the hook; but let us suppose that said line is in other respects in its normal condition. Let it be assumed that the operator at 15 *a* touches its terminal occurring in her section. The current will pass over the line and split-circuit, as before, and will pass to ground through the bell-magnet, receiver, and transmitter. This will energize the line and bell-magnet and cause it to draw its armature down. The telephone-buzzer *a* does not respond, for the shunt-circuit of the line is broken at the contact *r* and the resistance of the line 2 cannot be varied by the bell-magnet, so the telephone-buzzer cannot respond. Such an indication means that the line is not in its normal condition, which is considered as a busy test for the good of the service. It may be mentioned incidentally that it will have 30 the effect of making subscribers place their instruments in their normal position, for as long as they leave them in abnormal positions they will know that no communication can be had with them.

35 Third. The lines 3 3' are represented in the drawings with telephones on the hooks and then as connected together, the flexible terminal of the line 3 being connected with the fixed terminal of the line 3' in the section B. 40 Suppose, now, that a subscriber presided over by the operator at *c* and a subscriber presided over by the operator at *d* desires either of the connected subscribers, the operators at *c* and *d* would touch the terminal of either of these circuits with their plugs. The two lines being connected, the resistance would be very much lowered, so that an increase of current would pass over the lines and through the split circuit. This would energize the magnet *l* and cause 50 said magnet to draw down its armature and break the telephone-buzzer circuit. The bells of both subscribers would ring and the bell-magnets would be cut in and out of circuit; but this would not be heard in either 55 telephone-buzzer *c* or *d*, for the circuits of these telephones are broken by the magnets *l*. We have shown in the drawings in the various diagrams the path of the current by arrows and represented the correct position 60 of parts under the different conditions. When the bell vibrates we have shown the clapper thereof as provided with two arrows pointed in different directions, and when the bell does not vibrate it is shown without arrows and 65 as having made one tap and resting against the bell. It will be noted in the third test just described, that while the bell-magnet may

be cut in and out as the bell vibrates the combined conductivity of the two lines, whether the bell be in circuit or shunted, is sufficient to 70 lower the joint resistance to such a degree as to cut out the telephone-buzzer. The condition shown in this case would represent a case where two subscribers had been talking to each other and had failed to call off—that is to say, the calling-subscriber has failed to 75 notify the central office that he is through talking. For the benefit of the service, when two lines are connected, whether conversation is being carried on over those lines or 80 not, and whether the telephones be on or off the hook, the lines are considered busy.

Fourth. Suppose two lines be connected having both phones off the hook, which would represent the condition of affairs when two subscribers were talking to each other. This is represented in the diagram by the lines 4 4', which are connected at the section B. If now some other subscriber in another section desires either of the subscribers *S*⁵ or *S*⁶ connected by said lines, the test given will be busy. For instance, if the operator at *d*' touches the terminal of the line 4 the current will pass over the split circuit, as in the last instance, the combined conductivity of the 95 two lines will be such as to increase the current in the branches of the split circuit, and will break the telephone-buzzer branch thereof. The subscriber's bell will not vibrate, but will make only one stroke and will be held 100 against the bell by the current passing through the bell-magnet. The shunts in this instance are broken by the telephone-hooks being raised by the springs, so that the buzzer *d*' will not vibrate, for both shunts are broken 105 and the bells cannot vibrate and cannot therefore cut in and cut out their resistance, so as to cause a vibration in the telephone-buzzer, although the circuit of the telephone-buzzer is not broken in this instance, for it will be 110 noted in this instance that both transmitters and receivers are in circuit, which will so increase the resistance of the lines 4 4', even though they be connected, that the circuit of the buzzer will be left undisturbed.

115 Fifth. Suppose, further, that the subscriber *S*⁸ has called for the subscriber *S*⁷ and the central office has made the connection, but that the subscriber *S*⁷ has not yet responded to the call. The telephone of subscriber *S*⁸ would be off the hook and the telephone of subscriber *S*⁷ would be on the hook. This condition of affairs is illustrated by the lines 5 5'. If now, before the subscriber *S*⁷ should respond, another subscriber should call for subscriber *S*⁸—say a subscriber presided over by operator at *a*', and this operator at *a*' should touch the terminal of the line 5'—there would be in this case an increase of current passing over the lines, for the reason that the resistance would be lessened by the conductivity 125 of the two lines. In this instance only one of the transmitters and receivers in the circuit of the connected lines 5 5', so that an 130

increase of current will pass through the magnet and break the buzzer-circuit. The circuit of the telephone-buzzer a' would be broken, the armature of the electro-magnet l being held away from its contact. The subscriber's bell S' would vibrate, cutting in and cutting out the bell-magnet; but this would have no influence on the telephone-buzzer a' , for the reason that its circuit is broken. The bell of subscriber S^s would not vibrate, but make only one tap. The bell-magnet would not be cut in and cut out of circuit, for the shunt is broken at r by the telephone-hook, so that the telephone-buzzer a' could not respond to the condition of line $5'$ whether its circuit was complete or not. The test in this instance would be busy, as it should be.

The foregoing cases represent all the conditions of affairs that can take place, and the correct test by our invention is given in every instance. It will be noted that our split circuit could not be used only when the lines had been equalized in resistance to some extent, for if a short line were signaled over by the split-circuit arrangement an increase of current would pass through the magnet l and give the busy test whether such line were in normal condition or not. It will be apparent, therefore, that our split circuit is dependent upon the use of some equalizing means. It will also be obvious to those skilled in the art that a split circuit calls for some peculiar form of bell-magnet circuits, for with some bell-magnet circuits the current would be varied to such a degree as to throw an excessive current into the split circuit, and would therefore cause the armature-lever of the bell-magnet to be held away from its stop, or would cause it to chatter, both of which would interfere with the tests.

It will be obvious to those skilled in the art that any other way of equalizing the circuit can be employed without departing from the spirit of our invention. It will be obvious, also, that other arrangements of the bell-magnet circuits may be made and still be within the spirit of our invention. So, too, other means of breaking the telephone-buzzer circuit when an excessive current is flowing over the wires may be used and still be within the scope of the invention. So, too, any other signal-receiving device could be used in place of the telephone-buzzer. If the lines emanating from the telephone-exchange were all practically of the same length, as in small towns, for instance, non-inductive resistances would be unnecessary. It will be apparent, therefore, that our invention, while dependent more or less upon equalizing the resistance of the lines, is not necessarily confined to such resistances.

We do not wish therefore to limit ourselves to the exact devices and arrangements set forth, but reserve to ourselves all that which comes within the scope of what we now desire to claim and secure by Letters Patent of the United States as our invention, which is—

1. A signaling-plug for the subscribers of a telephone-exchange system, embodying, essentially, a battery-terminal, a conducting-tip, and a resistance-coil, whereby the resistance can be graduated at the will of the operator, for the purpose described. 70

2. The combination, with a telephone-exchange system, of a signaling-plug consisting of a casing, a battery-terminal, as x , a movable conducting-tip, as y , extended into the casing, as described, a spiral spring, z , therefore, and a non-inductive resistance-coil in said casing, for the purpose described. 80

3. A telephone-circuit, a subscriber's bell-magnet, receiver, and transmitter, a shunt around said bell-magnet made and broken by the armature thereof, and a telephone-hook, also controlling the circuit of said shunt, 85 whereby the continuity of the line is always preserved, for the purpose described.

4. A signaling-circuit for the operator of telephone-exchange system in which subscribers are signaled from the central office, 90 consisting of a battery suitably grounded or connected with the return-circuits of the subscribers, a split circuit connected therewith, having a telephone-buzzer or test-instrument in one branch of said circuit, and a circuit maker and breaker for the first-mentioned branch of said split circuit arranged in the other branch thereof, for the purpose described. 95

5. The combination, with the switch-board, 100 of a telephone-exchange system, substantially as set forth, having telephone-lines extending therefrom to the various subscribers, a signaling-circuit passing around to the operators at the different sections of said switch-board, a battery therefor, a number of split circuits connected therewith in multiple arc, a telephone-buzzer in one branch of said split circuits, a circuit maker and breaker for the first-mentioned branch of the split circuits located in the second branch thereof, 110 and a signaling-plug connected with said split circuit, substantially as and for the purpose described. 105

6. The combination, in a telephone-exchange system, of a number of subscribers' wires emanating therefrom, equalizing-resistances for said lines to make them substantially uniform in resistance, bell-magnets located in said lines in the circuit of the subscribers' receivers and transmitters, and shunts for said bell-magnets controlled by the armatures of said bell-magnets, for the purpose described. 115

7. The combination, in a telephone-exchange system, of a number of individual subscribers' lines emanating therefrom, equalizing-resistances for said lines to make them substantially uniform in resistance, subscribers' bell-magnets having shunts controlled by 120 the armatures of said magnets, and telephone-hooks, also controlling the circuit of said shunts. 125

8. The combination, in a telephone-ex-

- change system provided with a switch-board, substantially as set forth, of equalizing-resistances for the lines emanating therefrom, a subscriber's bell-magnet located in each of 5 said lines, a shunt therefor controlled by the armature of said bell-magnet, a telephone-hook, also controlling the circuit of said shunt, a signaling apparatus at the central station, consisting of a battery in electrical communication with the aforementioned lines, a split circuit connected therewith having two branches, in one of which a telephone-buzzer or signal-receiving device is located, a circuit maker and breaker for said circuit located in 10 the second branch of said split circuit, and a terminal in electrical communication with said split circuit for signaling over said lines.
9. The combination, in a telephone-exchange system provided with a switch-board, 20 substantially a set forth, of a number of subscribers' lines emanating therefrom, equalizing-resistances for said lines, a subscriber's bell-magnet located in each of said lines, a shunt therefor controlled by the armature 25 thereof, a telephone-hook, also controlling said armature, a signaling-circuit at the central station passing therearound to each subscriber at the different sections of the switch-board, a battery therefor with suitable electrical 30 connections, split circuits connected in multiple arc with said signaling-circuit and passing to each operator, a signal-receiving device in one branch of said split circuit, a circuit-breaker for the latter branch of the split cir- 35 a circuit located in the second branch thereof, and a signaling-plug connected with said split circuit, for the purpose described.
10. The combination, in a telephone-exchange system, of a number of subscribers' lines emanating therefrom, a subscriber's bell-magnet in each of said lines, a shunt therefor controlled by the armature of said bell-magnet, a telephone-hook, also controlling the circuit of said shunt, a signaling-circuit at the central office, consisting of a battery having 40 suitable electrical connections, one or more split circuits emanating therefrom, in one branch of which a signal-receiving device is arranged, and a magnet in the other branch of said split circuit, for the purpose described. 45
11. A testing means for telephone-circuits, embodying, essentially, a test-instrument, circuit and battery with suitable electrical connections, and a circuit-breaker for said test-instrument operated by a predetermined amount of current, whereby when two lines are connected and the resistance brought to a predetermined value the current will cut said test-instrument out of circuit. 50
- In testimony whereof we have hereunto set 60 our hands and affixed our seals, this 7th day of May, 1888, in the presence of the two subscribing witnesses.
